US0D1075417S

(12) **United States Design Patent** (10) Patent No.: **US D1,075,417 S**
(45) Date of Patent: ** May 20, 2025

(54) **SIPPY CUP**

(71) Applicant: **Comotomo 2022 Inc.**, Sunnyvale, CA (US)

(72) Inventors: **Sang-Pyo Kim**, Los Altos, CA (US); **Yong Hyun Kyung**, Gwangmyeong-si (KR)

(73) Assignee: **Comotomo 2022 Inc.**, Sunnyvale, CA (US)

(**) Term: **15 Years**

(21) Appl. No.: **29/880,547**

(22) Filed: **Jul. 25, 2023**

(51) LOC (15) Cl. **07-01**

(52) U.S. Cl.

USPC **D7/534**

(57) **CLAIM**

The ornamental design for a sippy cup, as shown and described.

DESCRIPTION

FIG. 1 is a perspective view of a sippy cup, showing our new design.

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The portions shown in broken lines in the figure form no part of the claimed design.

1 Claim, 7 Drawing Sheets
